PUMP

John Ogrinc, East Norwalk, Conn.

Application March 15, 1938, Serial No. 195,934

6 Claims. (Cl. 103—103)

This invention relates to pumps of the centrifugal type, and more especially to an improvement in centrifugal pumps whereby greater pumping efficiency and greater pumping pressure may be developed.

As is well known by those skilled in the art, centrifugal pumps embody a series of vanes, which as they rotate, project fluid from the spaces defined by the vanes outwardly from the said spaces, because of the centrifugal force developed by the rotation of the impeller of which the vanes are a part. In reality, the vanes of the centrifugal impeller really throw the pumped fluid outwardly and keep it there by constantly beating it, so that considerable friction is developed with resulting eddy currents, keeping down of course, the efficiency of the pump, and limiting the pressure head which it will develop.

Because of this defect inherent in centrifugal pumps, it is generally necessary where high lifts are required, to use several stages of pumps, and thus develop the necessary pressure and lift. Certain prior art constructions have considered the possibility of limiting the opening through which the liquid escapes from each of the spaces defined by the vanes of the impeller. This naturally increases the velocity of the liquid leaving the impeller, and undoubtedly increases the pressure head.

The improvement which I have developed is best adapted for use with a centrifugal impeller, in which the openings through which the liquid must escape from the spaces between the vanes, is restricted as just set forth, but it should be understood that my invention may be utilized with the usual type of centrifugal pump well known in the art, if that is desired.

Before describing my invention generally, and then specifically, I should like to indicate that I have not as yet developed the entire theory on which my pump structure is based, my experience with my improved pump being a practical one, and based entirely on the building of structures embodying what I now believe to be preferred embodiments of my basic conception. I do not wish this fact to limit the patent monopoly which I may be granted, since undoubtedly, my basic conception may be embodied in various pump structures by those highly skilled in this art.

My centrifugal pump embodies confining means spaced between the impeller and the discharge side of the pump, which I shall term pressure chamber in this specification, these confining means having ports which alternately shut off the flow from the spaces between the impeller vanes,

and then allow the flow of liquid from the said spaces to the pressure chamber. Because of this arrangement, the fluid in each of the spaces defined by the vanes of the impeller is released for outward movement at periodic spaced points in the rotation of the impeller, so that the centrifugal pressure is allowed to build up and then to be suddenly released, thereby giving the action which I so much desire to obtain.

As a preferred embodiment of my invention, I use an impeller formed by a circular plate having a rim and a series of vanes extending from the plate and terminating in the rim. In one modification of the invention, it is the plate portion of the impeller which has openings through which the fluid escapes from the spaces between the vanes into the pressure chamber. A valve plate is interposed between the plate of the impeller and the pressure chamber, and functions as the confining means to which I have alluded above. This valve plate has a series of ports which alternately allow flow from the impeller and shut off the flow from the impeller to the pressure chamber.

In a second modification, the openings are formed in the rim portion of my impeller, and a circular sleeve-like member having ports, controls the flow from the impeller to the pressure chamber, in the same manner as the valve plate above described. It should be made quite clear at this point, that the circular rim and the circular plate may conceivably be formed separate from the vanes of the impeller and act as part of the confining means without being integral with the vanes of the impeller. All this is a natural development which may follow my basic disclosure and concept.

I shall now refer to the drawings in which two preferred modifications of my invention are shown. Fig. 1 is a section taken along lines 1—1 of Fig. 2, while Fig. 2 is taken along lines 2—2 of Fig. 1, Figs. 1 and 2 showing one form of my invention. Figs. 3 and 4 show a second form of my invention, Fig. 3 being taken along lines 3—3 of Fig. 4, while Fig. 4 is taken along lines 4—4 of Fig. 3.

Referring now more particularly to the drawings and especially Figs. 1 and 2, the intake pipe of my pump is designated by reference numeral 10, a ball check 11 being placed to restrict an opening 12 in a control sleeve 13, the purpose being to maintain fluid in the pump structure so as to keep the pump primed. It is obvious that the ball 11 will lift to a point limited by a pin 14 as the pump operates, the stoppage of the pump

allowing the ball to drop and shut off the downward flow of fluid.

The intake pipe 10 is screw threaded into a lower housing plate 15, relatively to which rotates the impeller 16 which has a series of vanes 17 extending from an integral plate portion 18. The vanes terminate in a rim 19, as is clearly shown in the drawings, and to this rim 19, through screws 20, there is secured a plate 21. This plate 21 has a central opening 22 through which the fluid flows into the various spaces 23 defined by the vanes 17, the fluid being projected from the said spaces by the centrifugal force developed as the impeller 16 rotates. It is conceivable, of course, that the plate 21, like many of the other parts that I have described and shall describe, may be eliminated without affecting very much the operation of my pump. It is only possible to determine empirically whether certain of my parts are absolutely essential, or may be modified or eliminated without affecting the basic operation of my pump.

In the modification of Figs. 1 and 2, an opening 24 is formed leading from each of the spaces 23 through part of the rim 19, and then through the plate 18, terminating on the upper surface 25 of the said plate. A central shaft 26 is screw threaded at 27 to a central lug 28 of the impeller, and acts to rotate the impeller through this connection. The shaft 26 passes at 29 through a valve plate 30 which is secured by bolts 31 to the bottom housing plate 15. A stuffing box construction is denoted in general by reference numeral 32, and acts to prevent leakage of any fluid from the pump along the bearing of the shaft 26.

The valve plate 30 has a series of openings or ports 33 preferably shaped as is shown in Fig. 2, these ports lying in position to communicate with the openings 24 leading from each of the spaces 23 defined by the vanes 17. It is quite obvious that rotation of the impeller will force fluid through the openings 24 and through the ports 33 into the pressure chamber, to be described presently. It is quite obvious, furthermore, that during part of the rotation of the impeller, some of the openings 24 will be under the solid portion of the valve plate 30, so that no fluid may flow at that time from the said spaces 23, which are then shut off.

During such time, the pressure will be built up in the shut off spaces 23 to approach the maximum, so that the fluid will flow outwardly under said pressure through the openings 24 when the said openings come into communication with the ports 33. In the preferred embodiment of my invention, three of the spaces 23 will be shut off against the flow of liquid therefrom, while three are in communication through the ports 33 with the pressure chamber. In view of what I have indicated generally above, and in view of the specific explanation just set forth, the action of the pump will now appear quite obvious to those skilled in the art.

The pressure chamber of my pump is defined by a casting 35 secured through stud bolts 35a to the rim portion 30a of the valve plate 30. The fluid will flow from the pressure chamber 36 defined by the casting 35 into the outlet pipe 37, all as is quite clearly shown.

I shall now describe a second form of my invention in which the impeller construction is the same as that of Figs. 1 and 2, except that for openings 24 leading from the spaces 23 of the impeller, I substitute openings 24a which extend through the rim 19 of the impeller, all as is quite

clearly shown. Instead of a valve plate such as the valve plate 30 of Figs. 1 and 2, I utilize a sleeve-like valve 40 secured by stud bolts 41 to the base plate 15, and having ports 42 therein which function exactly as do the ports 33 of the valve plate in Figs. 1 and 2.

Instead of the casting 35 of Figs. 1 and 2 used to define the pressure chamber there, I use a casting 43 into which the fluid will flow through the openings 24a and ports 42, and into the outlet pipe 37, all as is quite clear.

I now claim:

1. In a combination of the class described, an impeller of the centrifugal type having a series of vanes defining a series of separate compartments, relatively small discharge openings formed in the impeller and leading to each of said compartments, a pressure chamber into which the fluid carried between the vanes of said impeller is discharged through said openings, and means whereby the fluid in each of the compartments is placed into communication with said pressure chamber at least twice during each revolution of the impeller and each time during a substantial portion of each revolution of said impeller while placing said spaces out of communication during the remaining portion of each revolution.

2. In a combination of the class described, an impeller of the centrifugal type having a series of vanes defining a series of separate compartments, relatively small discharge openings formed in the impeller and leading to each of said compartments, a pressure chamber into which the fluid carried in said impeller compartments is discharged, at least two ports functionally interposed between the said impeller compartments and the said pressure chamber, said ports being of such size and so positioned as to place the fluid carried in the said compartments into communication with said pressure chamber during a substantial portion of each revolution of said impeller while placing said compartments out of communication during the remaining portion of each revolution.

3. In a pump of the class described, an impeller of the centrifugal type having a series of vanes projecting from a circular plate, a rim projecting from said plate and into which said vanes extend whereby each pair of vanes define a compartment in which fluid is moved as said impeller rotates, a pressure chamber, a portion of one of the surfaces defining each of said compartments having a relatively small opening through which fluid may be forced out of said compartments by centrifugal force and into said pressure chamber, at least two ports functionally interposed between said openings and said pressure chamber, said ports being of such size and so positioned as to place the fluid carried in the compartments into communication with said pressure chamber during a substantial portion of each revolution of said impeller while placing said compartments out of communication during the remaining portion of each revolution.

4. In a pump of the class described, an impeller of the centrifugal type having a series of vanes projecting from a circular plate, a rim projecting from said plate and into which said vanes extend whereby each pair of vanes define with said rim and plate a compartment in which fluid is moved as said impeller rotates, a pressure chamber, a portion of one of the surfaces de-

fining each of said compartments having a relatively small opening through which fluid may be forced out of said compartments by centrifugal force and into said pressure chamber, a series of ports functionally interposed between said openings and said pressure chamber, said ports placing the said openings alternately into and out of communication with said pressure chamber several times during each revolution as said impeller rotates.

5. In a pump of the class described, an impeller of the centrifugal type having a series of vanes projecting from a circular plate, a rim projecting from said plate and into which said vanes 15 extend whereby each pair of vanes define with said rim and plate a compartment in which fluid is moved as said impeller rotates, a pressure chamber, the plate portion of each of said compartments having a relatively small opening 20 through which fluid may be forced out of said compartments by centrifugal force and into said pressure chamber, a valve plate relatively to which said impeller plate rotates and functionally interposed between said openings and said 25 pressure chamber, said valve plate having a series of ports in communication with each of said openings several times in each revolution and during a substantial portion of each revolution of said impeller, whereby fluid will be placed under centrifugal pressure in each of said compartments

during rotation of said impeller and will be forced periodically by said centrifugal pressure from said compartments through said openings and said ports into said pressure chamber.

6. In a pump of the class described, an impeller of the centrifugal type having a series of vanes projecting from a circular plate, confining means preventing the outward flow of fluid by centrifugal pressure from the spaces between said vanes, transverse openings in said plate in each 10 of the spaces outlined by said vanes through which the fluid is forced outwardly by said impeller as said impeller rotates, a valve plate juxtaposed to said impeller plate and having a series of elongated slots acting as ports and relatively 15 to which the openings of said impeller plate move during the rotation of said impeller, whereby when said openings are opposite the solid part of said valve plate the flow of fluid from said impeller spaces is shut off, while when the said 20 openings are opposite said elongated slots the fluid will flow from said impeller spaces, said elongated slots being arranged so that certain of the openings are opposite elongated slots when 25 others of the openings are opposite solid portions of the valve plate, each of said openings communicating with all of said slots during each revolution of the impeller.

JOHN OGRINC. 30
